UNITED STATES PATENT OFFICE.

DAVID E. MCKEE, OF POTTER VALLEY, CALIFORNIA, ASSIGNOR OF ONE-
THIRD TO HUGH P. MCGEE, OF SAME PLACE.

LIFTING-MACHINE.

SPECIFICATION forming part of Letters Patent No. 363,476, dated May 24, 1887.

Application filed February 18, 1887. Serial No. 228,117. (No model.)

To all whom it may concern:

Be it known that I, DAVID E. MCKEE, of Potter Valley, Mendocino county, State of California, have invented an Improvement in Lifting-Machines; and I hereby declare the following to be a full, clear, and exact description of the same.

My invention relates to that class of lifting-machines in which the frame-work is a derrick-like structure; and my invention consists in a fixed mast, a boom hinged thereto and adapted to move through an arc in a vertical plane, said boom being jointed, so that it can also move through an arc in a horizontal plane, a block and tackle, and a winch for operating said boom, an adjustable extension for the boom, peculiarly operating and constructed lifting-fingers upon the end of the boom or its extension, and details of construction relating to the several adjustments and operations of the machine, all of which I shall hereinafter fully describe.

The object of my invention is to provide a simple and effective machine for raising weights of any description, either merchandise, sacks of grain, hay, or anything else required to be elevated, said machine being of a character easily transported and readily set up in the desired position.

Referring to the accompanying drawings for a more complete explanation of my invention, Figure 1 is a perspective view of my lifting-machine. Fig. 2 is a longitudinal section showing the engagement of the boom and its extension. Fig. 3 is a detail of the fingers I, showing the boards O.

A is the mast, which is to be fixed firmly in position so that it remains stationary.

B is the boom, hinged to the mast at b so that it may have a movement through an arc in a vertical plane.

C is the block and tackle, connected with the outer end of the boom, passing over suitable pulleys in the top of the mast, and down to the operating-winch c on the side of the mast, by which means the boom may be raised and lowered on its pivotal center, where it is joined to the mast.

The boom is jointed at b' and provided at that point with the hinge b'', so that the outer section of the boom may have a side move-

ment of its own. The two sections of the boom are held together normally by means of a lever, D, attached to the outer section, and having a shoulder, d, engaging a notch, d', on the inner section of the boom. The end of this lever is within reach of the operator, so that by taking hold of it he can release it from its engagement with the notch and by a side pressure force the outer end of the boom to move sidewise. The outer end of the boom is provided with a hook, E, for the attachment of any suitable weight or material to be lifted. F is an extension which is fitted upon the outer section of the boom in suitable stirrups or guides, f, so that it may have a longitudinal movement in the line of the boom for extension purposes. This movement is readily effected by means of a pinion, G, on a crank-shaft, g, said pinion meshing with a rack, f', on the under surface of the extension.

In order to prevent the extension from moving from its position to which it is adjusted and to control it, I have under the main boom a spring-actuated pawl, H, the end of which, operating through a slot in the boom, engages the rack on the under surface of the extension. On the outer end of the boom, or, as here shown, on the extension F, are the lifting-fingers I, consisting of curved tines made in the nature of a hay-fork. These tines are secured in heads i, which are pivoted on a transverse shaft mounted in the outer end of the extension. The inner pair of said heads have segmental gears i'. In the outer end of the extension is also mounted a crank-shaft, J, having at its center a crank, j, to which is attached a connecting-rod, k, passing backwardly over the extension to a pivoted lever, K.

The ends of the crank-shaft are provided with pinions L, which mesh with the segmental gears i' of the heads of the inner pair of lifting-fingers. To these gears, or to the shaft, are also attached the crank-arms m, from which connecting-rods M extend to the ends of the heads of the other pair of lifting-fingers. The operation of these lifting-fingers is as follows: By pulling the lever K back toward the mast the crank-shaft J is oscillated, whereby, through its pinions L engaging with the segmental heads i' of the pair of fingers, it turns said heads on their pivotal centers, and

at the same time, through the crank-arms *m*, connected with the heads of the other pair of fingers, it moves said fingers also, the movement of the two opposing sets of fingers being 5 toward each other, or closing upon the material to be grasped. By moving the lever in a reverse direction the lifting-fingers are separated.

The operation of the entire machine is as 10 follows: By paying out the tackle from the winch the boom is relieved, so that it descends by its own weight until its end is in such a position as to connect with or be connected with the material to be raised. In some cases the 15 extension part of the boom will be entirely removed and the weight will be suspended directly from the end of the main boom. If when lowered to position the boom is still to one side of the object to be raised, I can throw 20 its outer section over into the proper position by means of the lever *D*. The weight being now hooked on to the end of the boom, the winch is operated and the boom is raised on its pivotal connection with the mast, and, if 25 needed, its outer section is thrown around in front of or behind the mast to deposit its load.

In case such material as hay or sacks of grain has to be raised, I adjust the extension part of the boom, and by means of the crank-shaft and 30 pinion run said extension in or out along the boom to suit the position of the material to be raised. The boom being lowered and adjusted as before, the lifting-fingers of the extension fit over the material to be raised. The lever *K* is 35 then operated to close the fingers, and the elevation takes place, as before described. In case of lifting sacks of grain I would use small transverse boards *O* to prevent the lifting-fingers from tearing the sacks.

40 The machine may be used in many positions, and is especially adapted to accompany a wagon, as its mast may be readily secured to some portion of the wagon, as by clamping it to the spokes of one of its wheels.

45 Having thus described my invention, what I claim as new, and desire to secure by Letters Patent, is—

1. In a lifting-machine, a stationary mast, in combination with a boom hinged to the mast 50 so as to move through an arc in a vertical plane, said boom being jointed and its sections hinged together, whereby its outer section may have an independent movement sidewise, a block and tackle for elevating the boom on its 55 pivotal connection with the mast, and a winch for operating the block and tackle, substantially as herein described.

2. In a lifting-machine, a stationary mast, in combination with a boom hinged to the mast, 60 whereby it may have a movement through an arc in a vertical plane, said boom being jointed and its sections hinged together, whereby the outer section may have an independent movement sidewise, the lever *D*, by which the two 65 sections are locked together and the outer section operated, a block and tackle for elevating

the boom, and the winch on the mast for operating the block and tackle, substantially as herein described.

3. In a lifting-machine, a stationary mast, 70 in combination with the boom hinged to the mast and jointed, whereby it may have a movement through an arc in a vertical plane and its outer section have a movement sidewise, the longitudinally-adjustable extension fitted 75 and guided upon and moving in the line of the boom, the block and tackle for operating the boom, and the winch on the mast for operating the block and tackle, substantially as herein described.

4. In a lifting-machine, a stationary mast, 80 in combination with a boom hinged thereto, whereby it may have a movement in a vertical plane, said boom being jointed and its sections hinged together, whereby its outer section 85 may have a movement sidewise, the lever *D*, for locking the two sections together and operating the outer section, the longitudinally-adjustable extension *F*, mounted upon and moving in line with the boom, the block and 90 tackle *C*, for operating the boom, and the winch *e* on the mast, for operating the block and tackle, substantially as herein described.

5. In a lifting-machine, the stationary mast, the boom connected therewith and adjustable, 95 as described, the block and tackle for operating the boom, and the winch on the mast for operating the block and tackle, in combination with the extension *F* on the boom, guided by the stirrups *f*, and the means for longitudinally 100 adjusting said extension, consisting of the crank-shaft *g*, the pinion *G* thereon, and the rack *f'* on the under side of the extension, substantially as herein described.

6. In a lifting-machine, the stationary mast, 105 the boom connected therewith and adjustable, as described, the block and tackle for operating the boom, and the winch on the mast for operating the block and tackle, in combination with the extension *F*, mounted upon the boom, 110 the means for longitudinally adjusting the extension, consisting of the crank-shaft *g*, the pinion *G* thereon, and the rack *f'* on the under surface of the extension, and the spring-actuated 115 controlling-pawl *H*, by which the extension is controlled, substantially as herein described.

7. In a lifting-machine, the stationary mast and the boom connected therewith and adjustable, as described, the block and tackle for operating the boom, and the winch on the mast 120 for operating the block and tackle, in combination with the lifting-fingers *I* at the outer end of the boom, having the pivoted heads *i*, and the means for operating said fingers, consisting of the lever *K*, the connecting-rod *k*, the 125 crank-shaft *J*, the pinions *L* thereon, the segmental gears *i'* on the heads of one pair of fingers, the cranks *m* on the shaft, and the connecting-rods *M*, joining them with the heads of the other pair of fingers, substantially as 130 herein described.

8. In a lifting-machine, the lifting-fingers *I*,

having pivoted heads *i*, in combination with the means for operating said fingers, consisting of the lever *K*, connecting-rod *k*, the crank-shaft *J*, the gears *L*, the segmental gears *i'* on the heads of one pair of fingers, the cranks *m*, and the connecting-rods *M*, connecting said cranks with the heads of the other pair of fingers, substantially as herein described.

9. A lifting-machine comprising the fixed mast *A*, the boom *B*, pivoted thereto, whereby it may move through an arc of a vertical plane, said boom being jointed and its sections hinged together, whereby its outer section may have a movement sidewise, the block and tackle *C*, for operating the boom, the winch *c* on the mast, for operating the block and tackle, the longitudinally-adjustable extension *F* on said boom, and the adjustable fingers *I*, carried in the ends of said extension, all combined substantially as herein described.

10. The lifting-machine comprising the stationary mast *A*, the boom *B*, hinged thereto and jointed, whereby it may have adjustments

as described, the lever *D*, for locking the sections of the boom together and operating its outer section sidewise, the block and tackle *C*, for elevating the boom, and the winch *c* on the mast, for operating the block and tackle, the longitudinally-adjustable extension *F* on the boom, the fingers *I*, carried in the end of the extension, having pivoted heads *i*, and the means for operating the fingers, consisting of the crank-shaft *J*, the lever *K*, connecting-rod *k*, the pinions *L* on the crank-shaft, the segmental gears *i'* on the heads of one pair of fingers, the cranks *m*, and the connecting-rods *M*, joining said cranks with the heads of the other pair of fingers, all combined, arranged, and adapted to operate substantially as herein described.

15 In witness whereof I have hereunto set my hand.

DAVID E. MCKEE.
